UNITED STATES PATENT OFFICE.

WALTER FERRIS, OF MILWAUKEE, AND SVANTE R. W. M. BAGER, OF SOUTH MILWAUKEE, WISCONSIN, ASSIGNORS TO BUCYRUS COMPANY, OF SOUTH MILWAUKEE, WISCONSIN, A CORPORATION OF WISCONSIN.

ROPE-THRUSTING SHOVEL.

Continuation of application Serial No. 322,261, filed September 8, 1919. This application filed August 3, 1921. Serial No. 489,408.

To all whom it may concern:

Be it known that we, WALTER FERRIS and SVANTE R. W. M. BAGER, both citizens of the United States, and residing at Milwaukee and South Milwaukee, respectively, in the county of Milwaukee and State of Wisconsin, have invented a certain new and useful Improvement in Rope-Thrusting Shovels, of which the following is a full, clear, concise, and exact description, reference being had to the accompanying drawings, forming a part of this specification.

This invention relates to power excavators, and more particularly, to power shovels in which power actuated devices are employed for effecting and controlling the shifting or thrusting action of the dipper handle.

The general aim of the present invention is to simplify and improve the construction and operation of devices of this character.

A more specific object is the provision of a simple and improved form of dipper thrusting device, capable of advantageous use in any type of power shovel irrespective of the character of prime mover with which the shovel may be provided.

Another object is the provision of a dipper thrusting device which, though designed to utilize the working tension in the hoisting cable, may be actuated from the power source, without necessarily requiring a rotation of the hoisting drum.

Another object is the provision of an improved dipper thrust gear actuatable from the prime mover and of such character that the dipper handle may be forcibly shifted in either direction without requiring the use of a reversing gear.

Another object is the provision of a dipper thrusting device in which a single cable associated with the power unit may be employed for effecting a shifting of the dipper handle independently of the hoisting action of the hoist gear.

Another object is the provision of a dipper thrusting device that may be operated and controlled from the hoisting and dragline drums, such as are ordinarily provided in certain types of power excavators.

Other objects and advantages will later appear.

One embodiment of the invention is illus-

trated in the accompanying drawings, in which:

Figure 1 is a side elevation of a power shovel embodying the novel features of the present invention.

Figure 2 is a detail view on a larger scale of a portion of the dipper thrust gear shown in Figure 1.

Figure 3 is a plan view of a portion of the boom and associated parts.

Figure 4 is a sectional view taken substantially along the line 4—4 of Figure 2.

For convenience of explanation, the invention is shown and will be described as embodied in a power shovel having a longitudinally shiftable dipper handle, although it is applicable, with little or no modification, to shovels of that type in which the dipper handle is shiftable horizontally.

This application is a continuation of our copending application, Serial No. 322,261, filed September 8, 1919, the power shovel shown and described herein being substantially identical with that disclosed in the application just mentioned. This shovel includes a wheeled truck 10, provided with a turntable 11, supporting a rotatable platform 12, in the usual manner. A hoisting winch 13 is mounted upon the platform 12. The hoisting winch is driven from any suitable power unit (not shown) through an appropriate gearing, a portion of which is shown at 14. The hoisting winch includes a main drum 15 and an auxiliary drum 16, such, for instance, as are commonly employed as hoisting and dragline drums in some well known types of power excavators. These drums are mounted for independent rotation, each being independently actuated through the gearing 14, and each being controlled by individual clutch and brake mechanisms (not shown) of any standard or approved construction.

A boom 17 is pivotally mounted, as at 17', upon the platform 12. A cable 18 and sheaves 19 are employed in the usual manner for adjustably supporting the boom in any desired position of inclination. The boom carries the usual dipper 20, and dipper handle 21, in such manner that the dipper handle is permitted both a swinging and shifting movement. In this instance, the dipper handle is mounted for lengthwise

movement in the pivoted saddle blocks 22, and is provided with the usual racks 23 for engagement with the gears 24 secured to the shipper shaft 25. The shipper shaft is 5 rotatably mounted in fixed bearings 26 secured to the boom. The construction and arrangement of parts thus far described is old and well known in the art, so that a further or more detailed description thereof 10 is deemed unnecessary.

As above pointed out, the present invention has to do with the provision of a novel means for effecting and controlling the shifting or thrusting action of the dipper handle. 15 This is accomplished by the use of novel cable connections between the dipper handle and the main power unit. These connections are such that by drawing in one line of cable the dipper handle is shifted in one direction, means being provided for opposing this action of this line of cable, to shift the dipper handle in another direction when this line of cable is paid out. The arrangement is preferably such that the dipper handle 20 may be shifted in either direction, either during the hoisting or the lowering of the dipper.

This may be accomplished in various ways, but in the type of shovel shown 30 wherein the shipper shaft 25 is geared to the dipper handle, this shifting or thrusting of the dipper handle may be conveniently effected through the shipper shaft. In the shovel shown, therefore, the shipper shaft is provided with a drum 29 keyed or otherwise fixed thereto. This drum is connected with the auxiliary drum 16 hereinabove referred to by means of a cable 28. One end of cable 28 is wrapped about and 35 anchored upon drum 16, while the other end is wrapped about and anchored upon the drum 29. The arrangement is such that, when this cable is drawn in, under the action of the drum 16, the drum 29 and 40 shipper shaft 25 are rotated and the dipper handle is thrust in one direction, under the action of the gears 24 and racks 23. In the shovel illustrated, the cable 28 is wrapped about the drum 29 in such direction 45 as to produce an inward thrust on the dipper handle when this cable is drawn in.

Various provisions may be made whereby this action of the cable 28 is opposed, so that when this cable is paid out the dipper 50 handle is shifted in the other direction. In this instance, the tension in the dipper hoisting cable 31 is utilized for this purpose. The hoisting cable may be arranged in various ways with this end in view. In 55 the shovel shown, however, this cable 31 is connected with the hoisting drum 15 in the usual manner, while the other end is secured to and wrapped about the drum 29, so as to form in effect a continuation of the 60 cable 28. Cables 31 and 28 will be herein-

after referred to as separate cables because of their distinctive functions, although they may or may not in fact constitute portions of one and the same cable. Cable 31 extends from the drum 15 over a sheave 32, 70 preferably mounted adjacent the outer end of the boom 17, through a padlock sheave 33, connected with the dipper, and thence back over a sheave 34 to the drum 29. The cable 31 is thus made to support the dipper 75 and the resulting tension therein is made to oppose the tension in the cable 28.

The cable 31, under the action of the hoisting drum 15, performs its usual functions of raising and lowering the dipper 80 and swinging the dipper handle 21 about the shipper shaft 25. In addition, however, the tension in this cable is made to oppose the tension in the cable 28, so that when the drum 16 is rotated to pay out the cable 85 28, the dipper handle is forced in a direction opposite to that in which it is moved when the cable 28 is drawn in. Thus it will be seen that the dipper handle is always under the control of the drum 16 and that 90 it may be forced in either direction without requiring rotation of the hoisting drum 15. Furthermore, the dipper may be raised or lowered at will by the hoisting drum 15, 95 in the usual manner.

To illustrate the operation of the shovel described, assume that the dipper is in the lower digging position, such as illustrated in dotted lines in Figure 1, and that the drum 16 is held by its brake against rotation. Upon rotation of the hoisting drum 15 in a clockwise direction, the hoisting cable 31 is drawn in, the dipper is raised, and the dipper handle swung about the shipper shaft. As long as the drum 16 100 is held against rotation the shipper shaft does not rotate and the dipper handle is held against outward shifting movement. If it is desired to force the dipper more firmly against the bank, this is accomplished 105 by releasing the drum 16 to pay out the cable 28. This permits the shipper shaft to rotate under the influence of the tension in the cable 31 and the dipper handle is forced outwardly. If, on the other hand, it 110 is desired to reduce the bite by withdrawing the dipper from the bank, it is only necessary to rotate the drum 16 in a clockwise direction so as to draw in the cable 28. This action effects a rotation of the shipper 115 shaft against the influence of the cable 31 in such direction as to shift the dipper handle inwardly.

When the excavating movement has been completed and the dipper is clear of the 120 bank, the dipper may be readily shifted to an extreme outward position, such as shown in full lines in Figure 1, and such as might be required for dumping purposes, by merely releasing the drum 16. To return 125

to the dotted line position, it is only necessary to release the drum 15 so as to pay out the cable 31 and thus lower the dipper, and to rotate the drum 16 in a clockwise direction so as to thrust the dipper handle inwardly to the position shown.

It will be noted that by the mechanism above specifically described, in which the dipper is supported from a point between 10 the ends of the cable 31 and in which the ends of this cable are independently controlled by the drums 15 and 16, respectively, the dipper may be raised or lowered slightly by a manipulation of either of the 15 drums.

Various changes may be made in the embodiment of the invention hereinabove described, without departing from or sacrificing any of the advantages of the invention 20 as defined in the following claims.

We claim:

1. A rope thrusting shovel comprising a working platform, a boom carried thereby, a driving mechanism supported thereon, a 25 dipper handle mounted for rotation on the boom, a dipper on the end thereof, a shipper shaft adapted to move the dipper handle longitudinally, a drum on the shipper shaft, a pair of winch drums on the working 30 platform, two cables wound about the drum on the shipper shaft and leading one of them directly to one of the winch drums on the working platform, the other to the dipper and thence back to the other winch 35 drum on the working platform, and means for manipulating both of said cables.

2. A rope thrusting shovel comprising a working platform, a boom carried thereby, a driving mechanism supported thereon, a 40 dipper handle mounted for rotation on the boom, a dipper on the end thereof, a shipper shaft adapted to move the dipper handle longitudinally, a hoisting winch on the working platform, a cable having two ends, 45 each of them separately controlled by the hoisting winch the bight of the cable being associated with the dipper and one side of the cable being associated with and adapted to control the shipper shaft.

50 3. A rope thrusting shovel, comprising a working platform, a boom carried thereby, a driving mechanism supported thereon, a dipper handle mounted for rotation on the boom, a dipper on the end thereof, a shipper 55 shaft adapted to move the dipper handle longitudinally, a drum on the shipper shaft, a hoisting cable wound about the drum at one end, the bight of the cable being connected to the dipper, and means for controlling the other end of the cable and means for controlling the rotation of the drum.

4. A rope thrusting shovel, comprising a working platform, a boom carried thereby, a driving mechanism supported thereon, a 65 dipper handle mounted for rotation on the

boom, a dipper on the end thereof, a shipper shaft adapted to move the dipper handle longitudinally, a drum on the shipper shaft, a hoisting cable wound about the drum at one end, the bight of the cable being connected to the dipper and means for controlling the other end of the cable and means for controlling the rotation of the drum, said means comprising a cable wound thereabout and means for manipulating it. 70 75

5. A rope thrusting shovel, comprising a working platform, a boom carried thereby, a driving mechanism supported thereon, a dipper handle mounted for rotation on the boom, a dipper on the end thereof, a shipper 80 shaft adapted to move the dipper handle longitudinally, a hoisting cable for the dipper associated with the shipper shaft to rotate the shipper shaft in one direction only, and means for rotating the shipper shaft in another direction to control the longitudinal movement of the dipper handle. 85

6. Means for operating an excavator dipper comprising a boom, sheaves at the end 90 thereof, a saddle block pivoted to the boom, a dipper handle sliding in the saddle block, means for thrusting and retracting said dipper handle, including a shipper shaft associated with the dipper handle, a drum 95 thereon, and two independently operated cables, one of them being passed over the sheaves and about the drum and anchored thereon so as to simultaneously tend to hoist and extend the dipper, the other cable being 100 passed directly about and anchored on the drum so as to resist rotation thereof under the tension of the first cable.

7. A rope thrusting shovel, comprising a working platform, a boom carried thereby, a driving mechanism supported thereon, a dipper handle mounted for rotation on the boom, a dipper on the end thereof, a shipper 105 shaft adapted to move the dipper handle longitudinally, means for simultaneously raising the bucket to cause it to excavate and rotating the shipper shaft to force the bucket against the work, and means for controlling and limiting the movement of the bucket toward the work, said last named means 110 comprising a separate line wound about the shipper shaft. 115

8. In a power shovel, means for thrusting the dipper against the work, comprising a dipper handle, a shipper shaft associated with it, a drum thereon and cables wound thereabout in opposite directions and extending away from the drum and separate means under control of operator for controlling the operation of said cables. 120 125

9. In a power shovel, means for thrusting the dipper against the work, comprising a dipper handle, a shipper shaft associated with it, a drum thereon and cables wound thereabout in opposite directions and extend- 130

- 4
16. A power shovel having an excavating dipper provided with a handle, a hoisting apparatus for hoisting and lowering said dipper and for effecting a shifting movement of said handle in one direction only, and means opposing the shifting action of said hoisting apparatus to control such shifting movement and to shift said handle in another direction. 75
17. A power shovel having an excavating dipper provided with a handle, means including a line of cable for hoisting and lowering said dipper and for effecting a shifting movement of said handle in one direction only, and means including a second line of cable opposing the shifting action of said first named means for controlling such shifting movement and for shifting said handle in another direction. 80
18. A power shovel having a dipper provided with a handle mounted for swinging and shifting movements, two independently 95 rotatable drums, means including a line of cable connected with one of said drums for shifting said handle in one direction only, and means including another line of cable connected with the other of said drums for 100 shifting said handle in another direction only.
19. A power shovel having a boom, a dipper having a dipper handle mounted thereon for swinging and shifting movements relative 105 thereto, two independently rotatable drums, means including a line of cable connected with one of said drums for shifting said handle in one direction only, and means including another line of cable connected with the other of said drums for shifting said handle in another direction only. 110
20. A power shovel having a boom, a dipper having a dipper handle mounted thereon for swinging and shifting movements relative 115 thereto, means including a drum on said boom for effecting and controlling the shifting movements of said handle, two additional drums, a line of cable connecting said first named drum with one of said last named drums for effecting rotation of said first 120 named drum in one direction, and a line of cable connecting said first named drum with the other of said last named drums for effecting rotation of said first named drum in another direction. 125
21. A power shovel having a dipper provided with a handle mounted for swinging and shifting movements, means including a line of cable operable under the weight of 130
15. A shovel having a boom, a dipper and dipper handle mounted thereon for swinging and shifting movements and biased toward shifting movement in one direction only, independently of whether said dipper 60 is being raised or lowered, and means including a cable for controlling such shifting movement and for effecting a shifting movement of said dipper handle in another direction. 65
16. A power shovel, means for thrusting the dipper against the work, comprising a dipper handle, a shipper shaft associated with it, a drum thereon and cables wound thereabout in opposite directions and extending away from the drum, a plurality of hoisting drums, the flexible ends of each of said cables being wound thereabout, one of said cables leading directly to its hoist drum, the other being intermediate its ends associated with the bucket as a hoisting cable, means for independently rotating both of said drums to take up the cables and means for limiting and controlling the 20 rotation of the drums in the opposite direction to control the paying out of the cables. 70
17. In an excavating shovel, a bucket, a slidably and rotatably mounted bucket handle, a hoisting cable for the bucket, means operated by the hoisting cable for thrusting the bucket into the work, and means for resisting the thrusting action of said first named means to limit and control the resulting movement of the bucket toward the work, said hoisting and resisting means being separately controlled by the operator. 85
18. In a power shovel having a dipper, the combination of means for thrusting the dipper against the work and for retracting it therefrom, comprising a shipper shaft, a drum thereon, and cables wound upon said drum and tending to rotate the drum in opposite directions, one of said cables being the hoisting cable, the hoisting and thrusting being separately controlled by the operator. 90
19. A shovel having a boom, a dipper and dipper handle mounted thereon for swinging and shifting movements, a hoisting drum associated with said dipper and dipper handle for effecting a swinging movement thereof, means including a cable operable independently of said drum for effecting a shifting movement of said handle in one direction when said cable is drawn in, and means opposing the action of said cable for effecting a shifting movement of said handle in another direction when said cable is paid out. 100
20. A shovel having a boom, a dipper and dipper handle mounted thereon for swinging and shifting movements and biased toward shifting movement in one direction only, independently of whether said dipper 60 is being raised or lowered, and means including a cable for controlling such shifting movement and for effecting a shifting movement of said dipper handle in another direction. 65

- 5 said dipper to shift said handle in one direction, means including another line of cable opposing the shifting action of said first named means for controlling such shifting movement and for shifting said handle in another direction, and independently controlled means for actuating said lines of cable.
- 10 22. In a device of the character described, the combination of a boom, a dipper carried thereby, a drum on said boom connected with said dipper, a hoisting drum, a line of cable connecting said drums, said dipper being connected with said cable at a point thereon between said drums, so that the tension in said cable tends to shift said dipper in one direction, and means operable on said first mentioned drum for shifting said dipper in another direction.
- 15 23. In a device of the character described, the combination of a boom, a dipper handle having a dipper carried by said boom, a drum on said boom connected with said dipper handle, a hoisting drum, a line of cable connecting said drums, said dipper handle and dipper being connected with said cable at a point thereon between said drums so that the tension in said cable tends to shift said handle in one direction, and means operable on said first mentioned drum for shifting said handle in another direction.
- 20 24. A power shovel having an excavating dipper, means including a cable for supporting said dipper, means for drawing in and paying out one end of said cable to raise or lower said dipper, and means cooperating with the other end of said cable for advancing or retracting said dipper.
- 25 25. A power shovel having a hoisting cable, means for independently controlling the opposite ends thereof, and a dipper associated with said cable at a point intermediate the ends thereof to maintain a working tension therein, said means being rendered effective by such working tension to advance said dipper toward the work or to retract it therefrom.
- 30 26. In an excavating shovel, a bucket, a slidably and rotatably mounted bucket handle, a hoisting cable for the bucket, means responsive to the weight of the bucket upon the hoisting cable for thrusting the bucket into the work, and means for resisting the thrusting action of said first named means, to limit and control the resulting movement of the bucket toward the work, said hoisting and resisting means being separately controlled by the operator.

In witness whereof, we hereunto subscribe our names this 26th day of July, 1921.

WALTER FERRIS.

SVANTE R. W. M. BAGER.
